H. C. MALLORY
ENGINE COOLING SYSTEM
Filed Sept. 3, 1921

1,480,282

UNITED STATES PATENT OFFICE.

HARRY C. MALLORY, OF NEW YORK, N. Y.; SUE R. MALLORY ADMINISTRATRIX OF
SAID HARRY C. MALLORY, DECEASED.

ENGINE-COOLING SYSTEM.

Application filed September 3, 1921. Serial No. 498,265.

To all whom it may concern:

Be it known that I, HARRY C. MALLORY, citizen of the United States, and resident of New York city, in the county of New York and State of New York, have invented certain new and useful Improvements in Engine-Cooling Systems, of which the following is a specification.

The general object of my present invention is to provide an improved engine cooling system of the type in which a cooling liquid is converted into vapor by the heat abstracted from the engine, and the vapor thus generated is condensed in a condenser forming a part of the cooling system. A more specific object of the invention is to provide an improved condenser for use in a cooling system of the type specified characterized by its simplicity and by the small structural differences between it and radiators commonly employed in present day automobile engine cooling systems of the water circulation type.

The various features of novelty which characterize my invention are pointed out with particularity in the claims annexed to and forming a part of this specification. For a better understanding of the invention, however, and the advantages possessed by it, reference should be had to the accompanying drawings and descriptive matter in which I have illustrated and described referred embodiments of my invention.

Of the drawings:

Fig. 1 is an elevation partly in section of an engine cooling system;

Fig. 2 is a section on the line 2—2 of Fig. 1; and

Fig. 3 is a small scale section taken similarly to Fig. 2 illustrating a modification.

In the drawings and referring first to Figs. 1 and 2, A represents the cooling liquid jacket for the cylinders A¹ of an ordinary internal combustion engine. An inlet A' is provided at the bottom of the jacket space for the cooling liquid which will ordinarily be water, or a water and alcohol mixture, and A² represents the jacket outlet for vapor which also serves as the overflow outlet for the cooling fluid. The outlet A² is connected by a conduit C, which may advantageously include a flexible section C' to the upper chamber B² of the condenser. The hot well B⁵ of the condenser B is connected to the jacket inlet A' by a return connection

including pipe sections D and D' and a circulating pump E which is driven from the engine shaft through the reducing gear E', the latter also driving the usual fan G through a belt G. An air pipe H running from the condenser to the suction intake manifold L of the engine forms a means for withdrawing air from, and maintaining a vacuum in the condenser. The air pipe H is shown as provided with a steam trap or valve I permitting the escape of air, but restricting the escape of steam from the condenser through the pipe H. As shown the pipe section D' comprises a goose neck portion extending to the top of the jacket and connected to the condenser by a vent pipe F to prevent the jacket from draining into the condenser when the circulating pump is stopped. M represents a safety valve limiting the pressure in the condenser and K represents a vacuum relief valve, preferably adjustable, which is adapted to open and admit air to the condenser when the pressure therein falls to a predetermined minimum.

The condenser is provided with distributed condensing surfaces B' which advantageously, as shown, are formed by horizontal pipes having their ends expanded and connected together to thereby form portions of the front and rear walls of the condenser shell. In the respect noted the condenser is similar in construction to radiators commonly used in an automobile cooling system of the water circulating type. The tubes B' are spaced away from the top of the condenser shell to provide the inlet chamber B², and are spaced away from the bottom of the condenser shell to provide the hot well space B⁵, and are spaced away from the side edges of the condenser shell to provide channels B⁴, B⁸ and extending from the chamber B² to the chamber B⁵.

The channel B⁴ forms a chamber in which the air in the condenser tends to concentrate. The air outlet H opens from this chamber, and advantageously the equalizing connection F and the vacuum breaking valve K are also connected to this chamber. The upper end of the channel B⁸ is separated from the inlet chamber B² of the condenser by a baffle B⁶ which also covers the upper portion of the bank of condensing tubes, and diverts liquid and vapor entering the chamber B² into the upper end of the chan-

nel B³. A baffle B⁷ prevents the passage of vapor into the bottom of the intertube space from the hot well B⁵ adjacent the channel B⁴, and a downwardly extending portion of the baffle B⁷ normally provides a water seal preventing vapor from passing into the lower end of the channel B⁴ from the vapor space in the hot well B⁵.

In the contemplated mode of operation of the cooling system shown in the drawings, liquid is forced into the jacket A through the inlet A' at a rate at least as great as, and preferably in excess of the rate at which liquid is evaporated in the system by the heat absorbed in the jacket A. When liquid is being forced into the jacket at a rate in excess of the rate of evaporation, some of the liquid will pass from the top of the jacket through the outlet A² and conduit C into the inlet chamber B² of the condenser B. Under some conditions all of the vapor generated by the heat absorbed in the jacket may be liberated in the jacket or in the conduit C so that the discharge from the conduit C into the condenser will comprise a lower stream of liquid and an upper stream of vapor, but under some conditions, the discharge into the condenser chamber B² and the conduit C will consist wholly or in part of boiling liquid from which vapor is liberated in the condenser. When liquid is supplied to the jacket inlet A' at the rate at which vapor is generated from the liquid heated in the jacket, only vapor and not liquid may enter the condenser from the conduit C, though in this case, under some conditions of operation, a substantial portion of the vapor generated in the system may be liberated within the condenser from the boiling liquid carried into the latter through the conduit C.

In any event, the vapor and any unvaporized liquid passing through the condenser chamber B² are diverted into the upper end of the channel B³, and are prevented from passing directly downward into the intertube space or into the upper end of the channel B⁴ by the baffle B⁶. The vapor entering the channel B³ passes from the latter into the adjacent open side of the intertube space, while the liquid entering the channel B³ passes through the channel B³ into the hot well chamber B⁵ without appreciable flow through the intertube spaces of the condenser. Even with the convex sides of the bank of tubes which exists with the oval form of condenser shown in the drawings, the downflowing water will have little direct contact with any of the tubes of the condenser except those immediately adjacent the channel B³. With the described construction the air in the condenser will tend to concentrate in the channel B⁴ and in the immediate adjacent portion of the intertube space. The flow of vapor into the inter-

tube space tends constantly to drive any air in the system toward the channel B⁴, and all vapor paths of flow into the channel B⁴ traverse sufficient condensing tubes to prevent any appreciable flow of vapor into the channel B⁴ under normal operating conditions. My improved condenser differs but slightly from radiators in common use in engine cooling systems of the water circulation type. Indeed the condenser shown in Figs. 1 and 2 of the drawings differs from one commercial type of engine cooling radiator only in the omission of a few of the upper tubes of the radiator and the addition to the radiator structure of the baffles B⁶ and B⁷. It is therefore a comparatively simple matter to convert an existing engine cooling system of the water circulation type into my improved cooling systems. Furthermore an engine cooling system of the boiling and condensing type constructed in accordance with the present invention may be readily operated as a cooling system of the water circulation type if occasion occurs for this. With the apparatus shown all that is really necessary to convert the system into a water circulating system is to close the valve H² and increase the amount of water in the system.

In the modification illustrated in Fig. 3, the channel B⁴ as well as the channel B³ is in free communication at its upper end with the inlet chamber B², and the baffle B⁶ serves to deflect water from the space B² into both of the channels B³ and B⁴, both of which, in this case, serve as water flow and steam distributing channels. In Fig. 3 the tubes B' are spaced in two banks or groups separated by a central, vertical air channel B³⁴, which extends upward from the hot well chamber B to or adjacent the baffle B⁶. The air outlet H opens, as may also the equalizing vent connection F, into the upper end of the channel B³⁴ which may advantageously be enlarged somewhat as shown. Baffles B^{7a} may advantageously be employed as shown to normally provide a water seal against the passage of steam from the lower ends of the channels B³ and B⁴ into the lower end of the air channel B³⁴. It will be obvious that the operation of the apparatus shown in Fig. 3 is essentially the same as that shown in the apparatus 1 and 2 except that in Fig. 3 air only has to cross half of the tubes B' to come from a distributing channel into the air channel from which it is withdrawn.

While in accordance with the provisions of the statutes I have illustrated and described the best forms of my present invention now known to me, it will be apparent to those skilled in the art that changes may be made in the form of my invention without departing from the spirit of my invention as set forth in the appended claims,

and that certain features of my invention may sometimes be used to advantage without a corresponding use of other features.

Having now described my invention, what I claim as new and desire to secure by Letters Patent, is:

1. In an engine cooling system, the combination with an engine cooling jacket, of a surface condenser comprising a shell and distributed condensing surfaces therein interposed between an inlet chamber at the top of the condenser and a water space at the bottom of the condenser, a connection leading from the jacket to said inlet chamber, means for returning water from said water space to the jacket, an air outlet opening from the condenser adjacent to its top and a baffle in said condenser interposed between said inlet chamber and said air outlet, said baffle, air outlet and condensing surfaces being so relatively disposed as to compel air or vapor passing to said outlet from said inlet chamber to follow an elongated path of flow through which said condensing surfaces are interspersed.
2. In an engine cooling system, the combination with an engine cooling jacket, of a surface condenser comprising a shell and distributed condensing surfaces therein interposed between an inlet chamber at the top of the condenser and a water space at the bottom of the condenser, a connection leading from the jacket to said inlet chamber, means for returning water from said water space to the jacket, and an air outlet opening from the condenser adjacent its top, a baffle interposed between said inlet chamber and said air outlet, said baffle, air outlet and condensing surfaces being so relatively disposed as to compel air or vapor passing to said outlet from said inlet chamber to follow an elongated path of flow in which said condensing surfaces are interspersed and means for closing said air outlet.
3. In an engine cooling system, the combination with an engine cooling jacket, of a surface condenser comprising a shell and distributed condensing surfaces therein interposed between an inlet chamber at the top of the condenser and a water space at the bottom of the condenser, a connection leading from the jacket to said inlet chamber, means for returning water from said water space to the jacket, an air outlet opening from the condenser adjacent its top, a baffle interposed between said inlet chamber and said air outlet, said baffle, air outlet and condensing surfaces being so relatively disposed as to compel air or vapor passing to said outlet from said inlet chamber to follow an elongated path of flow in which said condensing surfaces are interspersed, an air exhauster, and means for optionally closing said air outlet or connecting it to said air exhauster.
4. In an engine cooling system the combination with the engine cooling jacket, of a surface condenser comprising a shell, distributed condensing surfaces therein, interposed between an inlet chamber at the top of the condenser and a water space at the bottom of the condenser and grouped to form a water flow and vapor distributing channel leading downward from said chamber to said space, an air outlet opening from the condenser adjacent its upper end and horizontally separated from said channel by a space containing said condensing surfaces, a baffle within the condenser diverting liquid and vapor from said inlet chamber into said channel and preventing direct communication between said inlet chamber and said outlet, a connection from said jacket to said inlet chamber, and means for returning liquid from the lower portion of the condenser to the jacket.
5. In an engine cooling system the combination with a liquid cooling jacket, of a surface condenser comprising a shell and distributed condensing surfaces interposed therein between an inlet chamber at the top of the condenser and a water space at the bottom of the condenser, said surfaces being arranged to provide a water flow and vapor distributing channel extending downward past the condensing surfaces from said top chamber to said space, and an air space extending downward from said top chamber and separated horizontally from said channel by a group of said condensing surfaces, a baffle or partition separating the upper end of said air space from said top chamber, and serving to divert water and vapor from said top chamber into said channel, a connection from said jacket to said top chamber, means for returning liquid from said bottom space to the jacket, and means for discharging air from said air space.
6. In an engine cooling system the combination with a liquid cooling jacket, of a surface condenser comprising a shell and distributed condensing surfaces therein, arranged to provide a water flow and vapor distributing channel extending downward from the top to the bottom of the condenser, a connection from said jacket to the upper portion of the condenser, an air discharge connection opening from the condenser adjacent its upper end and separated horizontally from said channel by a group of interposed condensing surfaces, a baffle within the condenser shell for diverting liquid and vapor entering the condenser through said first mentioned connection into said channel and for preventing the direct flow of air and vapor from the top of the condenser into said air discharge connection, and means for returning liquid from the lower portion of the condenser to the jacket.
7. In an engine cooling system, the com-

2
bination with an engine cooling jacket, of a
surface condenser comprising a shell and
distributed condensing surfaces therein ar-
ranged to provide channels at the opposite
5 sides of the condenser between said con-
densing surfaces and the adjacent walls of
the condenser shell, a connection from said
jacket to the upper portion of the condenser,
10 a baffle within the condenser shell closing
the upper end of one of said channels, and
diverting liquid and vapor entering the con-
denser through said connection into the up-
15 per end of the other channel, means for dis-
charging air from said one channel, and
means for returning liquid from the lower
portion of the condenser to the jacket.

8. In an engine cooling system, the com-
bination with an engine cooling jacket, of a
surface condenser comprising a shell and

distributed condensing surfaces therein ar-
ranged to provide channels at the opposite
20 sides of the condenser between said condens-
ing surfaces and the adjacent walls of the
condenser shell, a connection from said
jacket to the upper portion of the condenser,
25 a baffle within the condenser shell closing
the upper end of one of said channels, and
diverting liquid and vapor entering the con-
denser through said connection into the up-
30 per end of the other channel, means for
admitting air to and discharging it from
said one channel and means for returning
liquid from the lower portion of the con-
denser to the jacket.

Signed at New York, in the county of
New York and State of New York, this
2nd day of September, A. D. 1921.

HARRY C. MALLORY.
